UNITED STATES PATENT OFFICE.

STUART MACPHERSON AND JAMES C. PORTER, OF PITTSBURGH, PENNSYLVANIA.

SPARK PLUG.

Application filed June 5, 1925. Serial No. 35,127.

To all whom it may concern:

Be it known that we, STUART MACPHERSON and JAMES C. PORTER, citizens of the United States, residing at Pittsburgh, in the county of Allegheny and State of Pennsylvania, have invented certain new and useful Improvements in Spark Plugs, of which the following is a specification:

This invention relates to a spark plug, and has for its object to provide, in a manner as hereinafter set forth, a plug that requires but little or no attention and with perfect ignition always present.

A further object of the invention is to provide, in a manner as hereinafter set forth, a spark plug including a plurality of auxiliary electrodes of spherical form shiftably mounted upon a base of conducting material and coacting with the central electrode of the plug in a manner to provide for the spark gap to remain constant, and to provide for the electrical discharge from the central electrode to contact with and scatter over the peripheral surface of the auxiliary electrodes, thereby producing a spark of greater intensity than that obtained in the plugs now generally used, and which further eliminates the extra expense of applying different types of unit intensifiers.

A further object of the invention is to provide, in a manner as hereinafter set forth, a spark plug having means to produce a circle of flame which will ignite weak gases under the most severe conditions.

A further object of the invention is to provide, in a manner as hereinafter set forth, a spark plug constructed in a manner to overcome the collecting of carbon to prevent fouling of the plug.

Further objects of the invention are to provide, in a manner as hereinafter set forth, a spark plug, which is simple in its construction and arrangement, strong, durable, thoroughly efficient in its use, of materially greater life than the plugs now in general use, readily assembled, and comparatively inexpensive to manufacture.

With the foregoing and other objects in view, the invention consists of the novel construction, combination and arrangement of parts, as hereinafter more specifically described and illustrated in the accompanying drawings, wherein is shown an embodiment of the invention, but it is to be understood that changes, variations and modifications can be resorted to which come with-

in the scope of the claims hereunto appended.

In the drawings where like reference characters denote corresponding parts throughout the several views:—

Figure 1 is a vertical sectional view of a spark plug, in accordance with this invention.

Figure 2 is an inverted plan.

Figure 3 is a section on line 3—3, Figure 1.

Figure 4 is a fragmentary view, in vertical section, of a modified form of the inner portion of the plug.

Referring to the drawings in detail, 1 denotes the plug body formed of insulation material and provided with a lengthwise extending passage 2, which merges into a lengthwise extending socket 3 of greater diameter than the passage 2, thereby providing a shoulder 4. The passage 2, at one end, opens at the outer end of the plug body 1, and the socket 3 opens at the inner end of the plug body 1, and the latter is provided intermediate its ends with a laterally extending annular boss 5, having a downwardly inclined outer edge 6 and an inwardly curved inner edge 7. The edges 6 and 7 provide shoulders.

The shell of the plug, which is formed of conducting material, is indicated at 8, and has its outer face formed with an annular shoulder 9, upon which is seated a washer 10, and engaging the latter is the inner edge or shoulder 7 of the plug body 1. The inner face of the shell 8, outwardly with respect to the shoulder 9, is provided with threads 11, and the shell 8 at the inner portion thereof is formed with peripheral threads 12.

The plug body 1 is extended in the shell 8 and has the inner end thereof terminating at a point removed with respect to the inner end of the shell 8, and said plug body 1 is removably secured in the shell 8, through the medium of a peripherally threaded gland 13, threadedly engaging with the threads 11 of the shell 8. Interposed between the inner end of the gland 13 and edge 6 of the boss 5 is a washer 14.

Extending through the plug body 1 is a central electrode 15, having a reduced inner portion 16 and a collar 17 on said reduced portion. The central electrode has the outer end terminal portion thereof peripherally threaded, as at 18, and mounted

thereon is a securing nut 19, a washer 20 and a binding nut 21. Supported on the collar 17 is a washer 22 which abuts against the shoulder 4. The washer 20 abuts 5 against the outer end of the plug body and is engaged by the securing nut 19. The collar 17, washers 20 and 22, nut 19 and shoulder 4 fixedly secure the central electrode 15 to the plug body 1.

10 The nut 21, in connection with the nut 19, clamps a circuit connection, not shown, to the electrode 15. The reduced portion 16 of the electrode 15 projects inwardly from the inner terminus of the shell 8. The 15 elements aforesaid are of known construction.

The inner terminus of the inner face of the shell 8 is bevelled to provide an annular shoulder 23, and formed integral with the inner end edge of the shell 8 is a cage or sleeve 24 of a thickness less than the thickness of 20 said shell 8. The inner face of the sleeve 24 is flush with the lower terminus of the shoulder 23.

25 The body portion of the sleeve 24 is cut away intermediate its outer and inner ends to provide a series of concentrically arranged openings 25, 26 and 27, and the inner face of the sleeve 24 below said openings is provided with a shoulder 28, and arranged 30 within said sleeve 24 as well as abutting against the shoulder 28 is a cup-shaped member 29 swaged as at 30, for fixedly securing it to the sleeve 24. The top edge 35 of the member 29 is bevelled, as at 31, and the bottom 32 of said member 29 is provided with a series of equally spaced circular openings 33, as shown four in 30 number. Formed integral with the inner face of the bottom 32, at the axis thereof, is a conoidal-shaped protuberance 34, of a length less than the height of the member 29 and which coacts with the edge 31 to provide a ball race for a pair of spherical 40 auxiliary electrodes 35 of greater diameter than either of the openings 33 and of a diameter to project above the edge 31 and in close proximity to the inner end of the 45 central electrode 15. The inner end of the electrode 15 is disposed to align with the axis of the protuberance 34. The distance 50 between the electrode 15 and the inner face of the shell 8 is less than the diameter of an auxiliary electrode 35, and the shoulder 55 23 constitutes a stop to arrest the outward movement of an auxiliary electrode.

The auxiliary electrodes shift around the ball race formed by the protuberance 34 and edge 31 and coact with the electrode 15 60 to provide the spark. The gap is formed between the inner terminus of the electrode 15 and the periphery of the auxiliary electrodes 35.

In the modified form shown in Figure 4, 65 the cup-shaped member 30 is dispensed with,

and in lieu thereof the ball race and protuberance are integral parts of a cage or sleeve which projects from the inner terminus of the shell 8. The cage or sleeve, which is referred to generally by the reference character 36, has a cup-shaped inner portion 37 of greater thickness than its outer portion 38. The inner portion 37 projects inwardly with respect to the inner face of the outer portion 38, and the projecting part of the inner portion 37 is bevelled, as at 39. The inner end of the portion 37 is provided with openings 40, corresponding to the openings 33, and said inner portion 37 is formed with a conoidal-shaped protuberance 41 corresponding to the protuberance 34. The bevelled inner end 39 and protuberance 41 coact to provide a ball race for the auxiliary electrodes 35. Otherwise than that as stated, the construction shown in Figure 4 is the same as that shown in Figure 1.

The construction set forth provides a spark plug wherein the electrical discharge is not at the same point of contact at all times, with respect to the central and auxiliary electrodes. The spherical auxiliary electrodes shifting on the ball race and the arrangement of said race and auxiliary electrodes with respect to the central electrode, provides for the spark gap to remain constant, allowing of the electrical discharge from the central electrode to come in contact with the auxiliary electrodes and scattered over the spherical surfaces of these latter which produces an intensified spark 100 materially greater than that obtained in the types of plugs now generally used, and furthermore eliminates extra expense of applying different types of unit intensifiers.

Owing to the construction and arrangement of the auxiliary electrodes, the collection of carbon is overcome as the vibration of the motor from the motion of its reciprocating parts causes the spherical electrodes to shift in the ball race, thereby overcoming the collecting of carbon as carbon will not collect on a moving part. As the auxiliary electrodes are constantly moving, they, as well as the race therefor, are kept clean, which overcomes the fouling of the plug, and under such conditions insures perfect ignition. Therefore, the disadvantages of carbon formation which are common to types of plugs now generally used, are eliminated.

The sleeve 24 or 36 and the parts carried thereby are so designed that the large openings in the sides of the sleeve and underneath the ball race provide that when the electrical discharge takes place, due to the shape of the auxiliary electrodes, the mechanical effect of the discharged matter is scattered presenting a large flame area to the gases for ignition. In this manner a higher degree of ignition is effected, and, further-

more, the auxiliary electrodes produce what may be termed a circle of flame which will ignite weak gases under the most severe conditions.

5 It is thought that the many advantages of a spark plug, in accordance with this invention, can be readily understood, and although the preferred embodiment of the invention is as illustrated and described, 10 yet it is to be understood that changes in the details of construction can be had which will fall within the scope of the invention as claimed.

What we claim is:—

15 1. In a spark plug a peripherally threaded shell, a central electrode extended from the inner terminus thereof, a cylindrical cage extended from the inner edge of the shell and provided with a row of circumferential- 20 ly extending rectangular openings above the transverse median of the cage, a cup-shaped member secured within the sleeve below said openings and having its bottom flush with the inner end of the cage and formed with 25 a series of openings, said member having centrally disposed means carried by the upper face of the bottom thereof, extending towards the openings in the cage and coacting with the edge of said member to provide

an annular ball race, and a plurality of 30 auxiliary electrodes of spherical contour shiftable in and projecting from said race and spaced from said central electrode.

2. In a spark plug a peripherally threaded shell, a central electrode extended from the inner terminus thereof, a cylindrical cage extended from the inner end of said shell and having a closure at its inner end formed with a series of openings, said cage further provided above its transverse median with 35 a circumferentially extending row of rectangular openings, said cage further provided on its inner face and intermediate its ends below said row of openings with an annular bevelled portion and on the upper face 40 of its closure with a conoidal-shaped centrally disposed protuberance coacting with said bevelled portion to form an annular ball race spaced from said closure, and a plurality of auxiliary electrodes of spherical contour shiftable in and projecting from 45 said race and associated with said central electrode.

In testimony whereof, we affix our signatures hereto.

STUART MACPHERSON.
JAMES C. PORTER.
